UNITED STATES PATENT OFFICE.

STEPHEN F. BRIGGS AND EDWARD N. JACOBI, OF MILWAUKEE, WISCONSIN, AS
SIGNORS, BY MESNE ASSIGNMENTS, TO BRIGGS & STRATTON CORPORATION, OF
MILWAUKEE, WISCONSIN, A CORPORATION OF DELAWARE.

PILLAR LOCK.

Application filed April 16, 1924. Serial No. 706,898.

To all whom it may concern:

Be it known that we, STEPHEN F. BRIGGS and EDWARD N. JACOBI, both citizens of the United States, and residents of Milwaukee, in the county of Milwaukee and State of Wisconsin, have invented new and useful Improvements in Pillar Locks, of which the following is a description, reference being had to the accompanying drawings, 10 which are a part of this specification.

This invention has for its object to provide a lock suitable for the doors of automobiles for locking the door latch mechanism by means of a key from the outside and has for its object to simplify the construction so as to effect economies in manufacture without sacrificing any of the essential characteristics of a lock of this type.

With the above and other objects in view 20 the invention consists in the pillar lock as herein claimed and all equivalents.

Referring to the accompanying drawings, in which like characters of reference indicate the same parts in different views,

25 Fig. 1 is a sectional elevation of a pillar lock constructed in accordance with this invention and showing also the lock dog to be engaged by the square stem of the pillar lock to be turned thereby for effecting a 30 locking engagement of the door latch;

Fig. 2 is a similar view on a different plane;

Fig. 3 is a front view thereof;

Fig. 4 is a sectional rear view thereof;

35 Fig. 5 is a sectional view on the plane of line 5-5 of Fig. 2, and

Fig. 6 is a perspective view of the spring.

In these drawings, 10 indicates the usual flanged bushing, within which the lock barrel 11 is adapted to be turned by means of the key 12 fitting therein. The barrel, instead of being entered from the back of the bushing, however, is entered from the front thereof and its shoulder 12' engages a flange 13 of the bushing to take the end thrust in one direction, while a thin sheet metal shell 14, which may be spun or otherwise fitted around the flange of the bushing, engages a shoulder 15 of the barrel to take end thrust in the opposite direction so that the barrel may be said to be rotatably mounted between the flange 13 and the edge of the shell 14. This shell has another very important purpose in that it may be made of highly

polished metal and, as it completely covers the front of the bushing, it dispenses with the necessity for nickel-plating and polishing the bushing.

The barrel 11 is provided with the usual slide tumblers 16, through the openings of which the key passes and by their fitting relation with the irregular key surface are brought to positions so that their ends lie flush with the surface of the barrel, permitting the barrel to be turned in the bushing. In two positions of the barrel, the tumbler slides may project from the barrel into grooves 17 of the bushing, thus permitting the key to be removed and preventing the turning of the barrel in the bushing. In order to form a detent indicating these two positions, a spring-pressed ball 18 is contained in an opening in the bushing and engages either of two notches 18' in the barrel, as shown in Fig. 5. The ball is pressed by a bowed leaf spring 19 with its ends loosely confined in slots of the cut-away portion of the bushing and said spring is retained against removal from said slots by having an opening 20 into which the ball projects. The ball is thus confined by the spring and the spring is confined by the ball without the necessity for further fastening means.

As it is not feasible to require the bushing to be accurately centered with respect to the lock dog 21 of the door latch, it is necessary that there should be a certain amount of freedom in the connection of the square stem 22 with the lock barrel, and this has usually been provided by pivotally mounting a flattened end of the stem in a slot of the lock barrel, with sufficient play between the parts to permit of disalignment and still provide the driving connection necessary for operating the lock dog. With this invention, however, a connection less liable to noise and wear is provided by forming the lock barrel with a square socket in its end sufficiently larger than the square stem 22 to permit of disalignment, but maintaining driving connections between them when the end of said stem is inserted therein and then loosely confining the stem in said socket by driving a wire staple 23 through openings in the barrel provided for that purpose, the legs of the staple passing through a groove 24 surrounding the stem, as shown in Figs. 1, 2, and 4, and being clinched at their ends.

To enable the end of the square stem 22 to readily find its way within the square opening of the lock dog 21 as the parts are assembled in the door, said end is tapered, 5 as at 25, to form a conical point.

It will be noted that the lock of this invention is greatly simplified in its construction, making it less expensive to manufacture by the elimination of screw threads, 10 rivets and various machine work and by the use of the polished metal shell which avoids the necessity for nickel-plating the bushing and at the same time serves to retain the lock barrel in place. The detent ball and 15 its spring interlock so as to be mutually dependent and the manner of fitting the square stem in the lock barrel more effectively accomplishes the purpose of maintaining a permanent driving connection and 20 still permitting of angular variations between the axis of the lock barrel and the axis of the lock dog, which is to be operated thereby for blocking the operation of the door latch to lock the door. This method of 25 connecting the parts furthermore, is one that is easily accomplished by the use of the ordinary tools and does not necessitate riveting or the like. The pointed end of the 30 square stem greatly facilitates the assembling of the lock as it enables the stem to find its way into the opening of the lock dog notwithstanding the dis-alignment of parts.

What we claim as new and desire to secure 35 by Letters Patent is:

1. In a lock, a bushing having a flange, a lock barrel rotatably mounted in the bushing and fitting against the flange, and a finished metal shell extending over the 40 end of the bushing and confining the lock barrel in place, the finish of said shell serving as the finish for the end of the bushing.

2. In a lock, a bushing having a flanged 45 end, a lock barrel rotatably fitting in the bushing and provided with a shoulder at its

end, and a thin sheet metal shell fitting around the end and flange of the bushing and against the shoulder of the lock barrel to confine the lock barrel in place.

3. In a lock, a bushing having an external 50 flange at its end, a polished metal shell extending over the face of the end of the bushing and around the flange thereof with an opening concentric with and of smaller diameter than the opening of the bushing, 55 and a lock barrel fitting in the bushing with a reduced portion extending through the opening of the shell.

4. In a lock, a bushing, a lock barrel mounted therein and provided with a de- 60 tent notch, a ball contained in an opening of the bushing, a leaf-spring having its ends loosely confined in slots of the bushing and having an opening through which the ball projects whereby the spring urges 65 the ball into engagement with the notch to form a detent and the projection of the ball through the opening of the spring prevents the displacement of the spring.

5. In a lock, a rotatably mounted lock 70 barrel, a square stem loosely fitting in a square socket in the end of the lock barrel and provided with a reduced neck portion, and a staple passing through the end of the lock barrel with its members embracing 75 the reduced neck portion of the stem.

6. In a lock, a bushing having an ornamental flanged end and provided with a grooved bore with the grooves extending to the front flanged end thereof, a lock barrel fitting within the bore of the bushing and a thin sheet metal skin covering for the ornamental flanged end of the bushing conforming therewith and covering the ends of the grooves and engaging the lock barrel 85 to form an end thrust bearing therefor.

In testimony whereof we affix our signatures.

STEPHEN F. BRIGGS.
EDWARD N. JACOBI.
